GENERATOR FOR COMPRESSING CARBON DIOXIDE

Edward M. Klopp, Seville, Ohio, assignor to The
Chemical Rubber Co., Cleveland, Ohio

Filed July 3, 1969, Ser. No. 18,052

Term of patent 14 years

Int. Cl. D15—10

U.S. Cl. D67—2

FIG. 1

FIG. 2

FIG. 3

FIG. 4

FIG. 5

FIG. 6

FIG. 1 is a perspective view of a generator for compressing carbon dioxide embodying my new design;

FIG. 2 is a plan view thereof;

FIG. 3 is a side elevation thereof;

FIG. 4 is a right end elevation thereof;

FIG. 5 is a left end elevation thereof; and,

FIG. 6 is a bottom view thereof.

I claim:

The ornamental design for a generator for compressing carbon dioxide, as shown and described.
